UNITED STATES PATENT OFFICE

ERNEST S. OSTLER, OF CHICAGO, ILLINOIS, ASSIGNOR TO STROMBERG ELECTRIC COMPANY, OF CHICAGO, ILLINOIS, A CORPORATION OF MAINE

CLOCK-CONTROLLED CONTACT DEVICE

Application filed August 10, 1925. Serial No. 49,196.

My invention relates to clock controlled contact devices, such as might be used in a master clock for controlling secondary clock mechanism.

5 One of the objects of my invention is to provide such a contact device which will require only a small amount of power to operate it.

10 A further object is to provide such a contact device which will be operated by an oscillatable member, and which will offer a balanced resistance to oscillation.

15 A further object of my invention is to provide such a device in which the oscillatable member is in the form of the spring finger provided with opposed stops.

20 A further object of my invention is to provide such a device with a removable conductor by means of which the frequency of the periodic contact may be changed.

In the drawings in which my invention is illustrated,

Figure 1 is a front elevation of the contact device and escapement which controls it;

25 Fig. 2 is a plan view of Fig. 1; and

Fig. 3 is a section on the line 3—3 of Fig. 1.

The construction shown comprises an escapement mechanism 1 and a periodically actuated switch device 2 controlled by the es-

30 capement. The switch device is so designed that it may be caused to make a contact on each oscillation of the verge shaft 3 and so that by removing a conductor strap, it will be caused to make a contact to close the circuit

35 only on each alternate oscillation of the verge shaft. The escapement mechanism itself may be of any usual or suitable construction comprising an escapement wheel 4, the verge 5 operated thereby and the oscillatable verge

40 shaft 3 on which the verge is mounted, this verge shaft transmitting impulse to the pendulum 6 through the verge wire 7 in the usual manner. The contact device comprises an upwardly extending finger 8 in the form of a leaf spring mounted on the verge shaft 3 and a pair of similar circuit closing devices on opposite sides of the upwardly extending oscillatable spring finger. The right hand circuit closing device comprises a pair of

45 leaf spring contact members 9 and 10, a pair

of metal stampings 11 and 12 on which the contact members 9 and 10 are mounted, respectively, an insulating base 13 on which the stampings are secured by screws 14, and a binding screw 16 threaded into the metal stamping 12. The insulating base 13 is mounted for pivotal adjustment on a supporting bracket 17 by means of a screw 18 extending through the bearing openings 19 in the bracket 17 and threaded into the insulating base. An adjusting screw 20 is provided for effecting the pivotal adjustment of the insulating base, this adjusting screw being threaded through an ear 21 on the supporting bracket 19 and provided with a lock nut 22 for holding it in adjusted position. The supporting bracket is secured on the main frame 23 by means of a pair of screws 24. The other left hand contact device is quite similar to that just described, except that in 70 the left hand contact device the binding screw 16 is threaded into the inner stamping 25, whereas in the right hand contact device the binding is threaded into the outer stamping 12. In order to hold both contact devices 75 against the respective adjusting screws, a coil compression spring 26 is placed between the two contact devices which tends to separate them.

The two outer stampings 12 and 27 are electrically connected by means of a curved conductor strap 28 which is detachably secured to the stampings by means of screws 29. In a similar manner the two inner stampings 11 and 25 are electrically connected by means 85 of a conductor strap 30 secured to the stampings by means of screws 29.

If both conductor straps 28 and 30 are in place, the circuit will be completed on each oscillation of the verge shaft. If the longer conductor strap 28 is removed, the circuit will be completed only on the right hand swing of the oscillatable lever spring. If the shorter conductor strap 30 is removed and the longer strap 28 left in place, the circuit will be completed between the binding screws 16 only upon the left hand swing of the oscillatable spring finger. In order to limit the oscillatory movement of spring finger 8, an insulating block 31 is mounted there- 100

on, which, in its movement, engages the upper ends of the inner stampings 11 and 25. The upper end of the oscillatory spring 8 is provided with an impact member or hammer 32 5 insulated from the spring itself, which engages the contact members 9 and 33 alternately and on its right hand swing moves the contact 9 into engagement with the contact 10, and on its left hand swing moves the contact 10 10 33 into engagement with the contact 34.

If both conductor straps 28 and 30 are in place on the left swing of the spring contact member, the circuit is completed from the left hand binding screw 16 through the stamping 15 contacts 33 and 34, long conductor strap 28 and stamping 12 to the right hand binding screw 16. On the right hand swing of the spring contact finger, the circuit is completed from the left hand binding screw 16 through 20 the stamping 25, short conductor strap 30, spring contacts 9 and 10 and stamping 12 to the other binding screw 16. Of course, if either one or the other of the conductor straps is removed, it will prevent the completion 25 of the circuit on one or the other of the swings of the oscillatory spring finger.

The operation requires a very small amount of power, due to the lightness of the spring finger 8 and the spring contact members 9, 30 10, 33 and 34. The two circuit closing devices afford a balanced resistance to the movement of the oscillatory leaf spring actuator. The movement of the leaf spring is limited by engagement of the insulating buffer 31 with 35 the upper ends of the stampings or brackets 11 and 25. By adjusting the screws 20 the contact devices may be moved toward or away from the leaf spring actuator 8 to vary the duration of the contact.

40 While I have shown but one form of my invention, it is to be understood that I do not desire to limit myself to this particular construction since many changes and modifications may be made therein without departure 45 from the scope of the following claims.

I claim:

1. The combination with a periodically oscillatable member of an oscillatable leaf spring mounted thereon, two base members 50 each carrying a pair of relatively movable cooperating contact members actuatable by the direct spring action of said oscillatable leaf spring, and positioning means for said contact members comprising a single resilient means coating between said base members and adjusting means for each of said base members opposing the action of said resilient means thereon.

2. The combination with a periodically oscillatable member, of an oscillatable leaf spring mounted thereon, two pairs of leaf spring contacts, the two contacts of each pair being normally out of engagement with each other and adapted to be moved into engagement with each other periodically by the di-

rect spring action of said oscillatable leaf spring, means for connecting the two pairs of contacts in parallel relation to each other, a supporting base member for each of said pairs of contacts, and means for mounting 70 said base members for adjustment with respect to said oscillatable leaf spring, comprising a spring coating between said base members to bias the same away from each other and a screw for forcing one of said base 75 members toward the other.

3. The combination with a periodically oscillatable member, of an oscillatable leaf spring mounted on said member, a pair of leaf spring contacts normally out of engagement with each other and moved into engagement with each other periodically by the direct spring action of said oscillatable leaf spring, a stop for limiting the movement of said oscillatable leaf spring to prevent it from causing excessive movement of said leaf spring contacts, and means for adjusting the relation of said leaf spring contacts with respect to said oscillatable leaf spring to vary the point at which said contacts are moved into engagement, said stop being movable with said contacts under the influence of said adjusting means.

4. The combination with a periodically oscillatable member, of an oscillatable leaf 95 spring mounted on said member, a leaf spring contact member actuated periodically by the direct spring action of said oscillatable leaf spring, a supporting member on which said leaf spring contact is mounted, said supporting member having a portion constituting a stop to limit the movement of said oscillatable leaf spring to prevent it from causing excessive movement of said leaf spring contact, and means for adjusting the position of said supporting member to move said leaf spring contact and said stop portion correspondingly with respect to said oscillatable leaf spring.

5. The combination with periodically oscillatable means having a normal amplitude of oscillation, of a pair of contact members periodically brought into contact with each other by the action of said oscillatable means, and means for ensuring uniform contact making action between said contacts comprising a yieldable oscillatable member for effecting contact between said contact members, a portion of which has an amplitude proportional to the amplitude of said periodically oscillatable means, and means for limiting the amplitude of a portion of said yieldable oscillatable member to a definite amplitude (less than that which it would otherwise have due to the normal amplitude of oscillation of 125 said periodically oscillatable means).

6. The combination with periodically oscillatable means having a normal amplitude of oscillation, of a pair of contact members periodically brought into contact with each 130

other by the action of said oscillatable means, and means for ensuring uniform contact making action between said contacts comprising a yieldable oscillatable member for effecting contact between said contact members, a portion of which has an amplitude proportional to the amplitude of said periodically oscillatable means, and means for limiting the amplitude of a portion of said yieldable oscillatable member to a definite amplitude (less than that which it would otherwise have due to the normal amplitude of oscillation of said periodically oscillatable means), said yieldable oscillatable member comprising a leaf spring mounted on said periodically oscillatable means.

7. The combination with periodically oscillatable means having a normal amplitude of oscillation, of a pair of contact members periodically brought into contact with each other by the action of said oscillatable means, and means for ensuring uniform contact making action between said contacts comprising a yieldable oscillatable member for effecting contact between said contact members, a portion of which has an amplitude proportional to the amplitude of said periodically oscillatable means, and means for limiting the amplitude of a portion of said yieldable oscillatable member to a definite amplitude (less than that which it would otherwise have due to the normal amplitude of oscillation of said periodically oscillatable means), said periodically oscillatable means comprising a verge shaft and said yieldable oscillatable member comprising a leaf spring extending upwardly from and mounted on said verge shaft.

8. The combination with periodically oscillatable means having a normal amplitude of oscillation, of a pair of contact members periodically brought into contact with each other by the action of said oscillatable means, and means for ensuring uniform contact making action between said contacts comprising a yieldable oscillatable member for effecting contact between said contact members, a portion of which has an amplitude proportional to the amplitude of said periodically oscillatable means, and means for limiting the amplitude of a portion of said yieldable oscillatable member to a definite amplitude (less than that which it would otherwise have due to the normal amplitude of oscillation of said periodically oscillatable means), one of said contacts being movably mounted, and stop means for definitely positioning said movable contacts when at rest.

9. The combination with periodically oscillatable means having a normal amplitude of oscillation, of a pair of contact members periodically brought into contact with each other by the action of said oscillatable means, and means for ensuring uniform contact making action between said contacts com-

prising a yieldable oscillatable member for effecting contact between said contact members, a portion of which has an amplitude proportional to the amplitude of said periodically oscillatable means, and means for limiting the amplitude of a portion of said yieldable oscillatable member to a definite amplitude (less than that which it would otherwise have due to the normal amplitude of oscillation of said periodically oscillatable means), and means for adjusting the position of one of said contact members with respect to said yieldable oscillatable member.

In witness whereof, I have hereunto subscribed my name.

ERNEST S. OSTLER.
